Atty.

UNITED STATES PATENT OFFICE.

RICHARD LESTER WILCOX, OF WATERBURY, CONNECTICUT, ASSIGNOR TO THE WATERBURY FARREL FOUNDRY AND MACHINE COMPANY, OF WATERBURY, CONNECTICUT, A CORPORATION OF CONNECTICUT.

DIE-SEPARATING MEANS.

Application filed October 31, 1921. Serial No. 511,805.

To all whom it may concern:

Be it known that I, RICHARD LESTER WILCOX, a citizen of the United States, residing at Waterbury, in the county of New Haven 5 and State of Connecticut, have invented certain new and useful Improvements in Die-Separating Means, of which the following is a specification, reference being had therein to the accompanying drawings.

10 My invention relates to die separating means, its principal object being to provide simple mechanism for separating the dies of an open die header or upsetting machine.

15 Among other aims and objects of my invention may be recited the provision of a device of the character mentioned with a view to compactness and in which the number of parts are few, the construction simple, 20 the cost of production small, and efficiency and operation high.

The improvements in the details and arrangement of parts will be apparent from an inspection of the accompanying drawings, 25 in connection with the description hereinafter contained, and wherein an embodiment of the invention is disclosed for the purpose of imparting a full understanding of the same.

30 Having more particular reference to the drawings and in connection with which like reference characters refer to corresponding parts in the several figures:

Figure 1 is a front elevation of a pair 35 of dies for a heading machine or the like with a portion of the supporting mechanism therefor and with my improved separating means connected therewith;

Figure 2 is a transverse sectional view 40 thereof taken generally upon line 2-2 of Figure 1;

Figure 3 is a perspective view of the cam block; and

Figure 4 is a front elevation of a pair of 45 dies similar to Figure 1, with the separating mechanism applied to the underside thereof.

It has heretofore been the practice to 50 separate the dies of an open die header or upsetting machine at the wire feed line by parting pins, separating pins or the like, an illustration of such means being shown in Letters Patent No. 1,104,090, dated July 21, 1914, particularly in Figure 4 thereof, and also in Letters Patent No. 1,108,958, dated

September 1, 1914, a heavy flat spring, not 55 shown in either of the above patents, bearing upon the upper end of each of the parting pins or separating pins, which move in a path at substantially a right angle to the movement of the dies. With such mechanism the die cap or other part or parts that support the pins must be machined with great care and exactness and each must be in correct alignment with each other and the groove formed by the angular corner 60 faces of the dies, when the dies are in proximity to the wire feed line. If the pins are not so arranged, the lower pointed end thereof will not register with said groove, thus having a tendency to cramp 65 the dies and apply an unequal pressure thereto at different points throughout their length. If this occurs, the dies may be separated more at one end than at the other, and if perchance the minimum separation 70 is at the inner end of the dies a defective feed of the wire results and the end of the wire may abut against the dies and stop the feed.

With the use of such pins the spring pressure 75 upon the end thereof is constant, therefore it requires not only a pressure sufficient to move the dies and cut off the wire but also to resist the pressure of the pin actuating springs, which pressure is constant upon 80 the top of one of the dies during its entire movement. There is no use for this pressure except when the dies are to be separated at the wire feed line, hence more power 85 is necessarily required to actuate the dies. 90 While more powerful mechanism is required to move the dies from the wire feed line to the upsetting line, the dies are usually returned by spring pressure, the strength 95 of which must of necessity also be increased to overcome the needless drag and pressure of the pins.

As the pins are of substantial length the element in which they are mounted must 100 of necessity be of substantial height to provide proper support therefor and this height, as well as the pin operating springs, requires space that can otherwise be advantageously utilized.

All of the above and other objections of 105 the heretofore conventional method for separating the dies are obviated in my improved device, which occupies the minimum

amount of not otherwise required space, the pressure is applied only when the dies are to be separated, the necessity of fine machining of the parts is entirely eliminated, and in these, and many other ways, produces results that are advantageous and insure certainty and efficiency in operation, and with mechanism that is of comparatively simple design.

- 10 Having more particular reference to the drawings, numerals 10 and 11 represent the dies, which are of the usual form with corner angular faces 12 which unite to form a V shaped groove substantially as shown in Figures 1 and 4, wherein the dies are near the wire feed line, this being coincident with the line 2-2 of Figure 1. A piece of wire designated 13 is shown in section at this feed line.
- 20 The bed plate upon which the dies are supported is designated 14, and the cap or cover over the top thereof 15.

All of the mechanism above described is of a well known form and operates in an equally well known manner and therefore needs no further description herein.

The means for actuating the dies is not shown herein for the above reason, but the same travel between the wire feed line and the upsetting line, which latter line is designated x-x in Figure 1. From the wire feed line to the upsetting line the dies are positively actuated by relatively powerful mechanism to cut off a piece of the wire rod but are usually returned from the upsetting line by spring mechanism.

Referring now particularly to Figures 1 and 2, there is associated with the cover 15 a cam plate 16 which is preferably dovetailed therein and having a cam face 17 thereon which inclines downwardly from the direction of the upsetting line toward the wire feed line. The use of this cam plate as shown is not necessary to the successful operation of the machine, nor the means for mounting the same in the cover, because the cam face may be formed upon the cover itself or may be secured in any other convenient manner.

50 The cam block 18 has two faces 19 which meet at their lower ends and are in substantially the same angular relation to each other as the faces 12 of the dies and a cam face 20, which has substantially the same angle as the cam face 17.

This cam block is mounted so that the meeting faces 19 point downwardly and rest against two of the faces 12 of the dies substantially as shown in Figure 1 with the cam face 20 thereon in contact with the cam face 17, when the dies are at the wire feed line, at which time the dies are separated slightly so as to permit the incoming wire to pass therebetween. When the dies move from the wire feed line to the upsetting line

the cam block 18 travels therewith, and the cam face 20 moves away from the cam face 17, thus permitting the meeting faces of the dies 10 and 11 to contact with each other. When the dies are in register with the upsetting line the relative position of the cam block 18 is substantially as shown by broken lines in Figure 1. When the dies are returned to the wire feed line the cam face 20 engages the fixed cam face 17 and is thereby moved downwardly forcing the dies apart slightly. Thus my improved die separating mechanism requires a minimum amount of space, pressure is only applied when required, that is, when the dies are at or near the wire feed line, and in these and other ways the objections to the mechanisms heretofore commonly utilized for separating the dies are eliminated and many obvious advantages secured.

I have shown in Figures 1 and 2 my improved mechanism as applied to the top side of the dies but obviously it will operate equally as well if applied to the underside thereof as shown in Figure 4, or if desired, it may be used upon both top and bottom. If used upon the bottom, the cam plate 16 is mounted in the bed plate 14^a instead of the cap 15^a, and the cam face 20 will remain in contact with the fixed cam face 17 instead of moving away from it as when used upon the top of the dies. Otherwise the construction and operation of the mechanism is the same as when the cam plate is above the dies.

There are minor changes and alterations that can be made within my invention, aside from those herein suggested, and I would therefore have it understood that I do not limit myself to the exact construction herein shown and described, but claim all that falls fairly within the spirit and scope of the appended claims.

Having described my invention, what I claim as new and desire to secure by Letters Patent, is:

1. In combination with the dies of a heading machine or the like, of means, for separating the dies, wherein each die has a face thereon that co-operates with a similar face upon another die to form a groove when the dies are in operative relation to each other; a block having angular faces thereon that move with the dies and project into said groove when the dies are substantially in line with the wire feed line; and a part having a cam face thereon in the path of movement of said block when the same is substantially in register with the wire feed line.

2. In combination with the dies of a heading machine or the like, of means, for separating the dies, wherein each die has a face thereon that co-operates with a similar face upon another die to form a groove when the dies are in operative relation to each other; a part having a cam face; and a non-rotat-

able block that projects into said groove and having contact with said cam face when the dies are substantially in line with the wire feed line.

5 3. In combination with the dies of a heading machine or the like, of means, for separating the dies, wherein each die has a face thereon that co-operates with a similar face upon another die to form a groove when the

10 dies are in operative relation to each other;

a part having a cam face; and a non-rotatable block that projects into said groove and having contact with said cam face when the dies are substantially in line with the wire feed line, said cam being formed so as to 15 prevent endwise movement of the block.

In testimony whereof, I have hereunto affixed my signature.

RICHARD LESTER WILCOX.
